UNITED STATES PATENT OFFICE.

MERRILL MOORE, OF CRESTON, IOWA.

BLOCK-MOLD.

1,084,355.

Specification of Letters Patent.

Patented Jan. 13, 1914.

Application filed June 19, 1913. Serial No. 774,633.

To all whom it may concern:

Be it known that I, MERRILL MOORE, a citizen of the United States of America, residing at Creston, in the county of Union 5 and State of Iowa, have invented certain new and useful Improvements in Block-Molds, of which the following is a specification.

This invention relates to concrete block 10 molds and one of the principal objects of the invention is to provide a mold of simple construction which can be connected up in series for receiving the concrete and which can be readily collapsed or withdrawn from 15 the block and which does not require a pallet for supporting the block.

Another object of the invention is to provide a sheet metal mold for building blocks which can be connected up in series to be 20 filled with cement by pouring the same in the molds and which will not require a pallet for supporting the blocks, said mold being readily removed from the blocks after they have become set.

25 Still another object of the invention is to provide a sheet metal mold comprising two side members held spaced apart the required distance by the end members, while the bottom of the mold is formed of a flexible water- 30 proof material which can be readily removed from the blocks after they have been molded and partially dried and set.

These and other objects may be attained by means of the construction illustrated in 35 the accompanying drawing.

Figure 1 is a perspective view of a number of block molds connected together in position for use, one of the ends of the mold being broken away; Fig. 2 is a top plan view 40 of one individual mold; Fig. 3 is a sectional view on the line 3—3 of Fig. 2 showing the mold filled with concrete; Fig. 4 is a detail perspective view of one of the ends of the mold boxes.

45 Referring to the drawing, the numerals 1 designate the side members of the mold box, said side members being preferably formed of sheet metal and provided with the inwardly projecting portions 2 near the center 50 thereof and the inwardly extending flanges 3 at the bottom. Inclined flanges 4 extend from the upper edges of the members 1.

The ends for separating one mold from the other consist of a flat plate 5 having the

ends bent oppositely at right angles as at 6 55 and when these ends are placed in position to separate the molds, the flanges 6 engage at their upper ends the inclined flanges 4 and said flanges 6 also engage the edges 60 of the members 1.

Extending across the bottom and resting upon the flanges 3 of the sides 1 is a bottom member 7 cut the required size from a sheet of flexible rubber roofing or similar material. 65

The manner of using the molds may be briefly described as follows: Any suitable number of the mold boxes are connected together by the ends 5 separating one box from the other. The flexible bottom 7 is placed 70 in position and these boxes are filled by pouring concrete material into them and after they have been filled flush with the upper surface, or nearly so, the faces are finished in any suitable manner and the 75 blocks permitted to dry. When the blocks are in condition to hold their shape without the mold, the latter is removed by removing the end pieces and sides serially from one end to the other of the series of boxes used, 80 thus leaving the blocks resting upon the bottom members 7. When sufficiently dried, the members 7 can be readily removed from the block.

From the foregoing, it will be obvious that 85 my invention is simple in construction, can be used quickly for molding poured blocks, and can be readily removed from the block when molded. It is also to be noted that I do not use a pallet for molding the blocks 90 and conveying them from place to place. This construction results in considerable saving, both in labor and material.

I claim:

A mold for concrete blocks comprising 95 two side members, said side members having inwardly extending flanges at their lower ends and inclined flanges at their upper edges, a flexible bottom for said mold and ends provided with oppositely disposed 10 flanges, said ends adapted to engage the flanges and edges of the side members.

In testimony whereof I affix my signature in presence of two witnesses.

MERRILL MOORE.
